UNITED STATES PATENT OFFICE.

EDWARD C. BURGESS, OF ISLINGTON, COUNTY OF MIDDLESEX, ENGLAND.

APPARATUS FOR COMBUSTION OF LIQUID FUEL.

SPECIFICATION forming part of Letters Patent No. 315,238, dated April 7, 1885.

Application filed July 22, 1884. (No model.) Patented in England May 5, 1884, No. 7,249; in France July 2, 1884, No. 163,111; in Germany July 6, 1884, No. 29,614; in Belgium July 7, 1884, No. 65,704; in Italy September 30, 1884, XXXIV, 200; in Austria October 3, 1884, No. 1,769; in Luxemburg October 17, 1884, No. 445, and in India November 17, 1884, No. 124.

To all whom it may concern:

Be it known that I, EDWARD CLINTON BURGESS, a citizen of England, residing at Islington, in the county of Middlesex, England, have 5 invented a new and useful Apparatus for Combustion of Liquid Fuel, of which the following is a specification.

My invention relates to apparatus for effecting combustion of liquid fuel—namely, oils or 10 liquid hydrocarbons generally—so as to produce a flame available for heating boilers or furnaces.

The accompanying drawing represents, in 15 section and partly in elevation, apparatus for this purpose according to my invention.

Within a fire-chamber, which may be of 20 brick-work, A, or might be the fire-box or flue of a boiler, I suspend a retort, R, of approximately hemispherical shape, with its 25 bottom somewhat rounded, so as to be thickest in its middle. From a water-cistern I connect a pipe, W, which, after passing in several convolutions around the retort, enters the retort near the bottom. From the upper 30 part of the retort I lead a pipe, S, to an injector-nozzle, J, and from a cistern containing the oil or liquid hydrocarbon I lead a pipe, O, to the annular space K surrounding the nozzle J. I provide under the retort a 35 shield, P.

The action of the apparatus is as follows: The retort R is in the first place heated by 40 burning under it any convenient combustible, such as a mass of shavings or fibrous materials soaked in oil, and then a small quantity of water is admitted by the pipe W, and 45 of oil or hydrocarbon liquid by the pipe O. The water is converted into steam, and this passes by the pipe S to the nozzle J, whence it issues as a jet carrying with it through the mouth L the oil or hydrocarbon liquid which 50 is broken into spray and dashed against the bottom of the retort. The jet also causes a current of air to enter by the tubular neck or 55 mouth T of the shield, and the mixture of the spray with the steam and air being ignited, a flame is produced which heats the

retort and the pipes. Shortly after the commencement of the action, when the retort and pipes have become sufficiently heated, the 50 supply of water and of oil or hydrocarbon liquid can be considerably increased by opening more or less cocks or valves in the supply-pipes W and O, and thus a large and powerful flame can be maintained, available 55 for heating boilers or furnaces.

I am aware that it has been proposed to construct hydrocarbon-burners of coiled pipes above an imperforate shield combined with water, steam, and oil pipes and an injector-nozzle under the shield, so that a spray of hydrocarbon mixed with steam and air and ignited is spread by the shield and caused to heat the coiled pipes for generating the steam to be used. Such, therefore, I do not broadly 65 claim.

Having thus described the nature of my invention and the best means I know for carrying the same into practical effect, I claim—

1. The combination, substantially as hereinbefore described, of a retort, a water-pipe connecting with the interior of the retort for delivering water thereinto, a shield arranged below the retort and having an opening therein, a pipe connecting at one end with the interior of the retort and provided at the other end with injector-nozzle arranged in the opening of the shield for delivering steam from the retort to said injector-nozzle, and a pipe for delivering liquid hydrocarbon about the 80 said nozzle in the opening of the shield, as and for the purposes set forth. 75

2. The combination, substantially as hereinbefore described, of a retort, a water-pipe connecting with the interior of the retort for introducing water thereinto, a shield arranged under the retort and constructed with a central pendent tubular neck, a pipe connected at one end with the interior of the retort and at the other end provided with an injector-nozzle arranged within the tubular neck of the shield, and a pipe for delivering liquid hydrocarbon about the said nozzle, substantially as set forth. 85 90

3. The combination, substantially as hereinbefore described, of a retort, a pipe convoluted around the retort and connected with the interior thereof for introducing water thereto, a shield arranged under the retort and constructed with a central tubular mouth, a pipe connected at one end with the upper part of the retort and provided at its other end with an injector-nozzle arranged within

liquid hydrocarbon about the said nozzle, as and for the purpose set forth.

In testimony whereof I have signed my name to this specification, in the presence of two subscribing witnesses, this 4th day of July, 15

A. D. 1884.

EDWARD C. BURGESS.
